US0D1058562S

(12) **United States Design Patent** (10) **Patent No.:** **US D1,058,562 S**
(45) **Date of Patent:** **** Jan. 21, 2025**

(54) **GAMING MONITOR**

(71) Applicant: **LG ELECTRONICS INC.**, Seoul (KR)

(72) Inventors: **Heeju Chang**, Seoul (KR); **Yeonjin Kim**, Seoul (KR); **Daihyung Ryu**, Seoul (KR); **Taejin Lee**, Seoul (KR)

(73) Assignee: **LG ELECTRONICS INC.**, Seoul (KR)

(**) Term: **15 Years**

(21) Appl. No.: **35/517,636**

(22) Filed: **Dec. 27, 2022**

(80) **Hague Agreement Data**

Int. Filing Date: **Dec. 27, 2022**

Int. Reg. No.: **DM/226097**

Int. Reg. Date: **Dec. 27, 2022**

Int. Reg. Pub. Date: **Jun. 30, 2023**

(30) **Foreign Application Priority Data**

Jul. 22, 2022 (KR) 30-2022-0029756

(51) **LOC (15) Cl.** **14-02**

(52) **U.S. Cl.**

USPC **D14/371**

(57) **CLAIM**

The ornamental design for a gaming monitor as shown and described.

DESCRIPTION

1.1 : Front perspective

1.2 : Rear perspective

1.3 : Front

1.4 : Rear

1.5 : Left

1.6 : Right

1.7 : Top

1.8 : Bottom

1.11 : Partial enlarged view of portion “**1.11**” of Reproduction **1.1**

1.12 : Partial enlarged view of portion “**1.12**” of Reproduction **1.2**

1.13 : Partial enlarged view of portion “**1.13**” of Reproduction **1.5**

1.14 : Partial enlarged view of portion “**1.14**” of Reproduction **1.7**

1.15 : Partial enlarged view of portion “**1.15**” of Reproduction **1.8**

(Continued)

The claimed design features the lighting applied to the lower center of the front and both sides of the back; the dash-dash broken lines indicate portions of the article that form no part of the claimed design; the dot-dash broken lines are included to show partial enlarged views only and form no part of the claimed design.

1 Claim, 13 Drawing Sheets
